UNITED STATES PATENT OFFICE.

JOHN C. ENGLISH, OF PHILADELPHIA, PENNSYLVANIA, ASSIGNOR TO VICTOR TALKING MACHINE COMPANY, A CORPORATION OF NEW JERSEY.

TALKING-MACHINE.

1,283,122.

Specification of Letters Patent. Patented Oct. 29, 1918.

Original application filed May 29, 1909, Serial No. 499,080. Divided and this application filed February 17, 1916. Serial No. 78,830.

To all whom it may concern:

Be it known that I, JOHN C. ENGLISH, a citizen of the United States, and a resident of the city of Philadelphia, county of Philadelphia, and State of Pennsylvania, have invented certain new and useful Improvements in Talking-Machines, of which the following is a specification, this application being a division of my Patent No. 1,181,655, issued May 2, 1916.

One object of this invention is to provide an improved form of talking machine cabinet including the provision of a structure built up of a plurality of associated sections or compartments adapted to be assembled into a complete improved talking machine cabinet. Moreover, this invention contemplates the provision of a structure in which the several sections may be prearranged to be associated in the manner indicated, or various forms of sections already known may be associated in the manner indicated to provide an improved form of completed talking machine cabinet of the character indicated. Further objects of this invention relate to a structure having the further capacity of permitting the removal of these several sections, if desired, to afford access or removal of any of the several parts of the talking machine mechanism, as well as permitting of a convenient method of transporting the several sections and the talking machine parts normally inclosed thereby, which may be readily assembled into the improved form of complete cabinet indicated.

Further objects of this invention relate to the various forms of construction and arrangement and association of elements as will more fully hereinafter appear in the specification and the appended claims.

In the accompanying drawings, Figure 1 is a front elevation of a talking machine, including a cabinet constructed in accordance with this invention; Fig. 2 a rear elevation of the same; Fig. 3, a fragmentary side elevation, partly in vertical longitudinal central section; Fig. 4, a perspective of a portion of the same; and Figs. 5 and 6, fragmentary perspectives of parts of the same.

Referring to the drawings, one embodiment of this invention comprises a cabinet consisting of three separable sections or portions arranged in vertical series, including a main or body portion 10, a base or amplifier portion 11 upon which the body portion

is mounted, and a cover 12 superimposed upon the body portion, these three sections being combined to provide a top compartment 13, an intermediate compartment 14, and a bottom compartment 15. The body portion 10 of the cabinet is substantially rectangular and includes a horizontal top wall 16, a horizontal bottom wall 17, parallel vertical side walls 18 and 19, a vertical front wall 20, and a vertical rear wall 21, the top and bottom walls 16 and 17 preferably projecting outwardly from each of the vertical walls 18 to 21. The cover 12 includes a flat vertical front end wall 25, a flat vertical rear end wall 26, and a transversely curved top wall 27. The end walls 25 and 26 are parallel and substantially semi-elliptical in shape, having straight lower edges which rest upon the upper surface of the top wall 16 of the body portion when the cover is closed, and upper edges which are curved longitudinally to correspond to the curvature of the top wall 27. The upper edges of the end walls 25 and 26 are provided upon their inner surfaces with marginal recesses 28 and 29, in which are secured the end edges of the transversely curved top wall 27, the upper surface of the top wall being flush with the upper curved edges of the end walls 25 and 26, and the top wall 27 and curved edges 25 and 26 being preferably substantially semi-elliptical in shape, as illustrated.

The base or amplifier section 11 of the cabinet projects laterally outwardly from each of the vertical walls 18 to 21 of the body portion 10 of the cabinet, and includes a horizontal rectangular bottom wall 30, vertical parallel side walls 31 and 32, a vertical rear wall 33, and a front vertical wall comprising two swinging doors or sound modifiers 34. These vertical walls of the base are preferably provided exteriorly along their upper and lower edges with longitudinal moldings 31' to 34' respectively, which are preferably integral with these walls respectively, and which serve to increase the rigidity of these walls and to add to the ornamental effect of the cabinet.

Arranged within the top compartment 13 is a horizontal rotary record support 35 which is mounted to rotate upon a vertical pintle 36 carried by the body or main portion 10 of the cabinet and rotated by actuating mechanism (not shown) arranged within the main compartment 10. Also

within the top compartment 13 is arranged a sound box 37, or other sound reproducing means, arranged to coöperate with a sound record 38 upon the record support 35. The 5 sound box 37 is mounted upon and communicates with one end of a hollow goose neck 39, the other end of which is connected to the free smaller end of a hollow tapering sound box arm 40 which extends in a substantially horizontal direction over the record support 35 and projects freely through 10 an arched recess 40' provided therefor in the lower edge of the rear vertical wall 26 of the cover 12. The larger end of the 15 sound box arm 40 is turned downwardly through an arc of substantially 90°, and is mounted upon the upper end of a hollow support 41 to oscillate with respect thereto in a fixed path about a fixed vertical axis. 20 The support 41 is arranged behind the rear wall 26 of the cover of the cabinet and, for compactness, extends in a recess 41' provided therefor in the rear edge of the top wall 16 of the body portion and is detachably connected to the upper end of a hollow 25 substantially vertical bracket 42, which is rigidly secured to the rear vertical wall 21 of the main portion of the cabinet by means of thumb screws 43, which extend through 30 an exterior base plate 44 and into an interior plate 45, thus clamping the two plates upon the opposite sides of the back wall 21 respectively. The hollow bracket 42 preferably flares downwardly, constantly increasing 35 in transverse section, and the lower portion of the bracket is curved longitudinally slightly outwardly, and then inwardly through an arc of about 90° and projects freely through an aperture 46 formed by a 40 comparatively large recess 46', arranged centrally in the upper edge of the rear vertical wall 33 of the base of the cabinet and a comparatively small recess 46'' arranged centrally in the rear edge of the bottom wall 45 17 of the body 10 of the cabinet. The bracket 42 terminates at its lower end in a horizontally transversely rectangular socket 47 arranged within the base 11 of the cabinet and relatively close to the rear 50 vertical wall 33 thereof.

The base or amplifier portion 11 of the cabinet is preferably utilized for entirely inclosing a horizontally arranged forwardly flaring transversely rectangular sound amplifier 48, the smaller end of which is rigidly secured in any suitable manner in the socket 47 of the hollow bracket 42, the larger end of the amplifier being arranged to deliver sounds through the outlet formed in the 55 front of the base 11 by the opening of the doors 34, but it is to be understood that the separate amplifier 48 may be omitted and the amplifier section or portion 11 of the cabinet may act to amplify the sound delivered thereto by the hollow bracket 42,

such construction being fully within the aim and scope of my invention.

The doors 34 are constructed and arranged so that, when closed, they will cover the entire space between the bottom wall 17 of the main portion 10 of the cabinet and the bottom wall 30 and the vertical side walls 31 and 32 of the base of the cabinet. The doors are also preferably arranged so that, when closed, they will overlap and 70 abut against the front end edges of the vertical side walls 31 and 32, and the outer end edges of the doors will then be flush with the outer longitudinal vertical surface of the side walls 31 and 32, and the inner 80 ends of the doors will meet centrally of the front of the cabinet. Each of these doors is provided with a knob 49 adjacent its inner end, to facilitate its operation.

For pivotally supporting the doors 34, 85 each door is provided on its upper edge, adjacent its outer end, with a plate 50 fitting into a recess provided therefor in the upper edge of the door and held in position by means of screws 51, or other suitable means, 90 the upper surface, the side edges, and the outer end edge of each plate being flush with a corresponding surface of the door. The lower edge of each door is provided with a correspondingly positioned plate 50' held in 95 position by screws 51'. Each of these plates is provided with a vertically projecting pintle 52, 52' rigid therewith, the two pintles upon each door being in vertical alinement with each other. Coöoperating respectively 100 with the two pintles 52, 52' on each door are two plates 53, 53', one of which, 53, is set into and is flush with the under surface of the bottom wall 17 of the main portion 10 of the cabinet, and the other of which, 53', is 105 set into and is flush with the upper surface of the bottom wall 30 of the base 11. Each of these plates, 53, 53', is held in position by means of screws 54, 54', or other suitable means, and is provided with an aperture 55, 110 55' in which the corresponding pintle fits snugly, but rotatably. The pintles 52, 52' of each door are preferably arranged between the planes of the inner and outer vertical longitudinal surfaces of the corresponding 115 side walls 31, 32, of the base, and the front ends of these side walls are recessed at their upper and lower corners respectively, as at 56, to receive the corresponding projecting corners 56' of the doors, as the doors swing 120 about their pintles. The construction is such that each door, when swung from its closed position outwardly through an arc of 90°, will be in longitudinal alinement with the corresponding side walls 31 or 32, the longitudinal surfaces of the door being flush with the corresponding longitudinal surface of the side wall, and the pivoted end of the door being substantially in abutment with the outer end of the side wall. Two spring

catches 57 are mounted in the upper side of the bottom wall 30 of the base 11 to hold the doors in closed position.

For detachably securing the base portion 5 of the cabinet to the main portion thereof, bolts 60, preferably having circular slotted heads 61, pass through washers 62, and apertures 63 provided therefor in the bottom wall 30 of the base, and are threaded into apertures 64 in plates 65 and 70, secured to the under surface of the bottom wall 17 of the main portion of the cabinet, by means of screws 71, or other suitable means, the washers and the heads 61 of the bolts 60 fitting in recesses provided therefor in the under surface of the said bottom wall 30 of the base 11. These latter plates 65 and 70 project downwardly from the under surface of the main portion of the cabinet and are arranged within and in contact laterally with the inner surfaces of the side and rear walls of the base 11 of the cabinet, to brace these walls and to facilitate the adjustment of the base in attaching it to the main portion 25 of the cabinet. Two of these plates 65 are each substantially L-shaped, and are arranged to engage the side and rear end walls of the base 11 in the angles formed by these walls, while the remaining two plates 70 are arranged one upon each side of the cabinet to engage the inner surfaces of the side walls of the base.

From the foregoing, it is evident that the sound box 37, tone arm 40, hollow bracket 35 42, and sound amplifier 48 may be quickly and easily detached and removed from the cabinet, for purposes of removal or replacement, or for convenience in transportation, merely by lifting the cover 12, unbolting and 40 removing the base 11, and taking out the thumb screws 43. This makes it possible to pack these parts separately for transportation and thus avoid any damage which might be likely to result were the talking machine, 45 including the cabinet illustrated, to be

shipped in an assembled condition. It will also be noted that upon the removal of the base portion from the body portion the pinches of the doors 34 are thereby released from their bearings and the doors are thus readily 50 dismounted. Furthermore, if after a talking machine has been constructed and assembled in accordance with this invention, it should become necessary to repair or replace the amplifier, or any other part of the machine, it is evident that this may be done 55 conveniently.

Another advantage resulting from the construction embodied in this invention is that by the provision of the separable cover 60 and base and the parts co-acting therewith, it is possible to conveniently convert a conventional talking machine of the exposed horn type into a machine of the inclosed horn construction.

Although only a single form has been illustrated in which this invention may be embodied, it is to be understood that the invention is not limited to the specific form shown but might be applied in various forms 70 within the scope of the appended claim.

Having thus fully described this invention, I claim and desire to protect by Letters Patent of the United States:

A talking machine cabinet including a 75 body portion providing a motor compartment, a hollow base arranged beneath and separable from the body portion and detachably held in fixed relation thereto, said base providing a sound amplifier compartment, and a hollow cover mounted upon the body portion and providing a sound reproducer compartment, the base and cover being 80 formed with openings through their exterior walls for the passage of a sound conduit.

In witness whereof, I have hereunto set my hand this 14th day of February, A. D. 1916.

JOHN C. ENGLISH.
